(57) **CLAIM**

The ornamental design for a gun sight, as shown and described.

DESCRIPTION

FIG. 1: is a perspective view of a gun sight in one embodiment thereof.

FIG. 2: is a top view of a gun sight in one embodiment thereof.

FIG. 3: is a bottom view of a gun sight in one embodiment thereof.

FIG. 4: is a right view with expanded detail of a gun sight in one embodiment thereof.

FIG. 5: is a left view of a gun sight in one embodiment thereof.

FIG. 6: is a front view of a gun sight in one embodiment thereof; and,

FIG. 7: is a back view of a gun sight in one embodiment thereof.

The broken lines are included for the purpose of illustrating environmental matter and form no part of the claimed design.
